UNITED STATES PATENT OFFICE.

ROBERT MURTON POOLE, OF MOUNT GAMBIER, SOUTH AUSTRALIA, AUSTRALIA.

PROCESS OF MANUFACTURING ILLUMINATING AND FUEL GASES FROM WOOD.

1,093,470.

Specification of Letters Patent. Patented Apr. 14, 1914.

Original application filed August 26, 1912, Serial No. 717,200. Divided and this application filed May 6, 1913. Serial No. 765,815.

To all whom it may concern:

Be it known that I, ROBERT MURTON POOLE, a subject of the King of Great Britain, residing at Mount Gambier, in the State 5 of South Australia, Australia, have invented certain new and useful Improvements in Processes of Manufacturing Illuminating and Fuel Gases from Wood; and I do hereby declare the following to be a full, clear, and 10 exact description of the invention, such as will enable others skilled in the art to which it appertains to make and use the same.

My invention relates to an improved process of manufacturing illuminating and fuel 15 gases from wood, and it consists in the steps and processes herein described and claimed.

This application is a division of application, Serial No. 717,200, filed by me August 26, 1912.

20 The illuminating gas can in known manner be strongly compressed, as for transport and storage, and can be expanded for consumption. It has special lighting power, and if burned on a Welsbach or like mantle 25 produces a light sufficiently approaching daylight in quality to allow of excellent night photography including portraiture with apparatus ordinarily used with day 30 photography. It allows of color work at night that is not now usual because of the difficulty of then distinguishing colors. It can be advantageously burned at lower pressure than suits coal gas—with under 2 inches of pressure excellent light is obtained. It is 35 not adversely affected like air gas made with benzine by changes of temperature.

My gas yields a blue flame, almost invisible by day, which affords a great heat and which is useful for cooking; it being free 40 from unpleasant odors or products of combustion. It is also valuable for internal combustion engines, as it deposits practically no carbon in the combustion chamber.

By retorting wood, and by the treatment 45 of its gases, I obtain charcoal and many by-products, the commercial value of which is much in excess of the cost of production. Some woods are of greater gas making value than others, and when hard and soft woods 50 are available I mix them. *Pinus insignis* produces more gas of high lighting quality (by the aid of incandescent mantles) than does an equal weight of eucalyptus, but the latter and hard woods generally are nevertheless valuable.

The accompanying drawings are diagrammatic, and not to scale, nor do they show relative sizes or proportions of parts, nor all such obvious details as the dampers, valves, hand holes, and so on that are installed in 60 practice, such minor points of engineering construction being already well understood.

In the accompanying drawings, forming a part of this application, and in which similar reference symbols indicate corresponding parts in the several views: Figure 1 is a diagrammatic view, with parts shown in section, illustrating part of an apparatus adapted to carry out my invention; and Fig. 2 is a similar view of the remaining portion 70 of such apparatus.

Referring to the drawings, *a* indicates one of a series of wood retorts connected by pipes *h* and *h'* with a header *h*³ for receiving the gases and vapors distilled from the 75 wood. The pipes *h'* are provided with downward extensions having one or more enlargements *h*⁵ for the deposit of heavy substances, a valve *h*⁶ being provided to permit ready removal of said deposits. The retorts 80 *a* are heated by suitable furnaces *c* provided with chambers *f* containing auxiliary retorts *b* and communicating with the discharge flues *f'*; dampers *f*² being provided in said flues for controlling the flow of the hot products of combustion through said chambers *f*. As shown in the drawings, the wood retorts *a* are provided at both ends with discharging doors exterior to the furnace walls and the 85 connections *h* and *h'* of said retorts are also 90 positioned exteriorly of the furnace to prevent injurious overheating thereof and to permit ready access for repairs. The retorts *a* are subjected to intense heat for causing a rapid distillation of the wood in order 95 to produce a maximum quantity of gases therefrom.

A pipe *h*⁴ conducts the vapor and gases from the header *h*³ to an elevated condenser *i* in which the different liquid products of 100 condensation are partially separated by gravitation, said pipe *h*⁴ discharging into the condenser *i* at a point below an outlet pipe *i*² for the lighter liquid condensations, such as pyroligneous acid. The heavy tarry 105 condensations are withdrawn from the condenser from time to time by an outlet pipe *i*¹⁰ provided with a valve *i*¹¹; an overflow pipe provided with a gage *i*¹⁴ being connected with said pipe *i*¹⁰ for preventing the 110

tarry condensations from rising in the condenser to the level of said outlet pipe i^2 of the latter. I have shown the condenser provided with a water jacket i' provided with 5 baffles i^3 , and with an inlet i^6 , and an outlet pipe i^7 for the cooling water; cooling tubes i^4 extending through the condenser in communication with said water jacket. The hot retort gases delivered by the pipe h^4 to the 10 condenser i are materially cooled by bubbling up through the cooled liquid condensations therein, and are conducted from the condenser by a pipe i^8 to the top of an annular condenser j' where their temperature 15 is further reduced and impurities condensed; the liquid condensations being withdrawn from said annular condenser by a valved drain j^1 . I have shown a pipe j^2 for conducting the gases from the bottom of the 20 condenser j' to the top of a duplicate condenser j^3 , and the gas can be thus circulated downwardly through any desired number of condensers. The annular condensers can be 25 readily water cooled in hot weather by flowing water downward over their exterior surfaces.

An exhauster x is shown for withdrawing the gases through a pipe x' from the condenser j^3 and delivering it through a pipe x^2 30 to a washer and purifier l containing lime water, or other suitable purifying substance for removing further condensations and a portion of the carbonic acid from the gases; the gas passing through the lime water into 35 a bell l^2 l^3 provided with a discharge pipe m . The pipes x' and x^2 are provided with valves and connected by a valved by-pass x^3 to provide means for cutting out the exhauster x 40 and directing the gas from the condenser j^3 to the purifier l . The purifier l is provided with a dished bottom having an outlet pipe l' controlled by a valve l^5 for drawing off the heavier substances deposited from the 45 gas.

The pipe m discharges the purified gas into a washer n provided with a gage glass n' , and maintained partly full of water which is renewed or freshened from time to time; the gas entering through a submerged 50 gravity-seated ball valve similar to the hereinafter described valve v' . The gas, containing hydrocarbons, such as ethane, methane, ethylene, and their homologues, is conducted by a pipe n^2 from the top of the washer n to the gas holder, and is there termed "gas y ".

The lighter liquid condensations are conducted by the pipe i^2 from the condenser to a receiver o^2 which has a valve-controlled 60 drain o^8 and communicates with the heated auxiliary retort b by a feed pipe o^3 provided with a controlling valve b^2 and a safety valve b' ; said valve b^2 being adjusted to maintain a drip or feed, proportionate to 65 the rate of distillation in the retort b . The

temperature of the retort b is regulated by the damper f^2 to drive off the gases and readily volatile matters, which are conducted by a pipe o^4 to a condenser coil o , from which the distillates are discharged into a tank o' ; a residue of tarry matters, creosote, etc. being drained from the retort b by a drain pipe provided with a valve b^3 . The tank o' is provided with a discharge pipe p controlled by a valve p^2 for conducting the 70 liquid distillates to a feed reservoir p' , which latter is shown provided with a sight feed device p^3 for furnishing a uniform supply of the liquid distillates to a vaporizer q within the heating chamber r' of a furnace 75 provided with a damper r^2 . The vaporizer q is heated to cause vaporization and partial gasification of the distillates supplied thereto, and the vapor is conducted therefrom through a valve-controlled pipe q^3 to a 80 header q' ; a valved by-pass p^4 connecting said header with the feed reservoir p' to equalize the pressure in the latter for regulating the flow through said sight feed p^3 . A pipe q^2 conducts the gases from the 85 vaporizer q to one or more highly heated retorts s in the furnace chamber r , for "fixing" 90 said gases. I have shown two retorts s connected at their rear ends to cause the gases to flow successively therethrough; 95 gases of high quality being conducted from said retorts s by a pipe s' leading to a condenser t . Such gases as are not condensed in the coil o pass from the distillate tank o' through a pipe o^6 provided with a non-return 100 check valve o^7 to said pipe s' , where they intermix with the gases from the retorts s . The condenser t is provided with a water jacket t' having inlet and outlet pipes t^3 and t^4 for the cooling water, and with a 105 valve-controlled drain pipe t^5 for removing the impurities condensed from the gas; an exhauster s^3 may be placed in the pipe s' if desired.

The cooled gases are conducted by a pipe 110 t^2 from the condenser t to a washer v^2 provided with a gage glass v^3 and a submerged gravity-seated ball valve v' , similar to the washer n previously described. The gas is conducted by a pipe v^4 from the top of the 115 washer v^2 to a separate gas holder and is there termed "gas z ". The gases " y " and " z " are stored in separate tanks, from which they are conducted to a gasometer where they are mixed to produce a high quality 120 gas.

The residues drawn off from the condensers i , j' , j^3 , and t , and also the residues from the tank o' and the retort b , constitute valuable by-products which can be utilized in 125 the arts in the usual manner.

I claim:—

The process, as described, for the manufacture of wood gas, consisting in retorting the wood to liberate the volatile products, 130

discharging the volatile products below the liquid level of similar pre-condensed products for condensing the same and causing the permanent gas to pass up through the liquid,
5 drawing off and purifying the permanent gas, drawing off and distilling the lighter of the condensed products, condensing such distillates, conducting away the permanent gases evolved during such distillation, heating to cause vaporization and partial gasifi-
10

cation of the condensed distillates, subjecting the gases to a fixing temperature, and mixing such fixed gases with the permanent gases.

In testimony whereof, I affix my signature, 15
in presence of two witnesses.

ROBERT MURTON POOLE.
